No. 37,075.

Patented August 9, 1904.

UNITED STATES PATENT OFFICE.

CURTIS S. CASAD, OF SILVERTON, COLORADO.

DESIGN FOR A PICTURE-FRAME.

SPECIFICATION forming part of Design No. 37,075, dated August 9, 1904.

Application filed July 15, 1904. Serial No. 216,744. Term of patent 14 years.

To all whom it may concern:

Be it known that I, CURTIS S. CASAD, a citizen of the United States, residing at Silverton, in the county of San Juan and State of Colorado, 5 have invented a new, original, and ornamental Design for a Picture-Frame, reference being had to the accompanying drawing, which forms a part of this specification.

This invention relates to a new, original, and 10 ornamental design for a picture-frame, the said design being illustrated in the accompanying drawing, which is a front view of a picture-frame showing my new design.

What I claim is—

The ornamental design for a picture-frame 15 as shown in the drawing.

CURTIS S. CASAD.
